UNITED STATES PATENT OFFICE.

THOMAS P. BROOKE, OF CHICAGO, ILLINOIS.

MOTOR.

1,247,788.

Specification of Letters Patent. Patented Nov. 27, 1917.

Original application filed November 14, 1912, Serial No. 731,244. Divided and this application filed August 10, 1916. Serial No. 114,107.

To all whom it may concern:

Be it known that I, THOMAS P. BROOKE, a citizen of the United States, residing at Chicago, in the county of Cook and State 5 of Illinois, have invented certain new and useful Improvements in Motors, of which the following is a specification.

This application is a division of my original application, Serial No. 731,244, filed in 10 the United States Patent Office November 14th, 1912, and the present invention relates more particularly to improvements in valve opening mechanism of a rotary type of motor of the class in which the force of the 15 explosion of the charge will exert an impulse on a movable piston head and a reaction upon the movable cylinder head, thereby utilizing the maximum power of the charge and resulting in a motor of a minimum weight of construction and the highest 20 efficiency in power, having the greatest number of explosions per revolution.

A further object is to provide an improved 25 rotary motor of the four cycle type, which will be compact and comparatively light in construction and having means whereby an explosion will be produced on every complete revolution of the cylinder.

A further object is to provide an improved 30 motor of this type whereby the gyroscopic torque in the propeller as well as in the motor will be overcome.

To the attainment of these ends and the 35 accomplishment of other new and useful objects as will appear, the invention consists in the features of novelty in substantially the construction, combination and arrangement of the several parts hereinafter more fully described and claimed and shown in the accompanying drawings illustrating the invention and in which:

Figure 1 is a longitudinal section view of 40 an improved motor of this type constructed in accordance with the principles of this invention with parts broken away and with parts omitted.

Fig. 2 is a detail sectional view taken on line 4—4, Fig. 1.

Fig. 3 is a detail view in elevation of the 45 inner face of one of the plates of the crank case.

Heretofore aeronautic motors have been constructed in such a manner that considerable 50 of the power obtained from the explosion of the charge has been wasted or lost.

In the present invention provision has been made to not only produce the greatest number of explosions for each revolution of the cylinder, but to also secure the maximum power from each explosion. This is 60 rendered possible by the provision in the present invention, of a rotary cylinder and a rotary crank for causing a relative reciprocation of the piston with the result that the force of every explosion is exerted directly upon two moving elements, so that there will be an impulse on the movable piston head and a reaction of the force on the end of the movable cylinder. This result is 65 accomplished largely by reason of causing the cylinder and crank shaft to which the piston is connected to rotate simultaneously in opposite directions and through other instrumentalities. The objectionable gyroscopic forces of the rotating parts is overcome by constructing and arranging the parts in such a manner that they will neutralize 70 or balance as will be apparent from the specification.

In the present form of the invention six 75 cylinders are shown but it is to be understood that any number of cylinders may be employed. That is to say, any equal number of cylinders, but preferably six, and one half of the number of cylinders is offset laterally with relation to the other half as will be seen more clearly in Fig. 7.

It is to be understood that the construction of each of the cylinders, piston rods and valve mechanism are the same and therefore 80 the specific description of one set will apply 85 equally as well to them all.

Referring more particularly to the drawings, the cylinders 10 are provided with shoulders adjacent the axis of rotation of 90 the cylinders and have inwardly extending flanges 12, preferably of a segmental shape extending about the axis to form substantially continuous flanges and these sections are secured together in any desired or suitable 95 manner.

Cover plates 15 and 16 (see Fig. 1) are provided to extend over the flanges 12 to form an air and gas tight crank case and these plates are held in position in any desired or suitable manner, such as by means of fastening devices 17 passing through the plates and the flanges for removably securing the plates in position. A hollow piston designated generally by the reference nu- 100 110

meral 18 is arranged to reciprocate in each of the cylinders and the piston rods 19 of one set or series of cylinders, to-wit: those which are arranged in alinement, are pivotally connected to a crank pin 20, in any desired or suitable manner, such as by means of a master piston rod having an enlargement 21, which is directly connected with the crank pin through the medium of an intermediate bushing 22. The other piston rods of the series or sets, are pivotally connected as at 23 with the enlarged portion 21 of the master piston rod as shown more clearly in Fig. 1. The piston rods of the 15 other set of cylinders are connected in a similar manner to a crank pin 24, which latter is connected with a revolving shaft 25 through the medium of a crank arm 26. The shaft 25 extends through one of the 20 cover plates 16, and is journaled in a suitable bearing 27, and the crank pin 20 is offset with respect to the crank pin 24 and connected thereto by means of a crank arm 28. Another shaft 29, which is preferably 25 tubular, extends through the cover plate 15 of the crank case, and is journaled in a suitable bearing 30. The shaft 29 is arranged in alinement with the shaft 25 and is connected with the crank pin 20 by means of a 30 crank arm or projection 31. The crank pins, crank arms and the connecting points between the piston rods and the respective crank pins are thereby compactly arranged and housed within the crank case. The 35 shaft 29 is preferably of tubular construction so as to permit the fuel to be supplied to the crank case through the shaft, and from the crank case, the fuel will pass into the cylinder through the hollow pistons and 40 past the piston valves 30*, which are located in the piston heads and are adapted to be seated and unseated automatically during the operation of the engine. The specific construction of the piston valves and the 45 operation thereof form no part of the present invention, but form the subject matter of a separate application.

The shaft 25 extends for any desired distance beyond the outer face of the plate 16 50 and secured to the extremity of the shaft is a propeller designated generally by the reference numeral 32, and this propeller is preferably constructed of three blades, and is of such a size and weight that, in combination with the crank and piston rods, just described, it will exactly balance the gyroscopic torque in the cylinders and pistons.

The mechanism thus far described is supported in a suitable frame constructed of any desired size and of any suitable material.

The frame preferably comprises spaced parallel members 33, 34. In order to support the structure, ball bearings 35, 36 are

provided in the frame and a portion of the shaft 29 projects beyond the cover plate 15 and is journaled in the bearing 35, while a projecting portion or hub 37 of the cover plate 16 is journaled in the bearing 36. 70 These members 33, 34 are tied together in any desired, or suitable manner and the frame is also provided with another member 38 adjacent and parallel with the member 34 but spaced therefrom. 75

Connected to rotate with the hub or projecting portion 36 of the cover plate 16 is a bevel gear 39 which also rotates about the shaft 25, and connected with the shaft 25 to rotate therewith is a bevel gear 40, 80 which is spaced from the gear 39 and rotates in opposition thereto. Arranged between these gears 39, 40 are connecting bevel gears 42 which are respectively journaled in suitable bearings in the frame, so that 85 when the parts are operated, the cylinders and crank case will rotate in one direction, while the cranks and the propeller rotate in the opposite direction.

In order to provide a support for the 90 shaft 25 where it passes through the member 38 of the frame, a ball bearing 46 may be provided through which the shaft passes. Thus it will be seen that the mechanism thus far described is supported in such a manner that the friction between the contacting and revolving parts will be reduced to a minimum. 95

Arranged at the end of each of the cylinders 10 is an exhaust valve 47, which is provided with a stem 48 projecting beyond the end of the cylinder and a spring 49 is provided and surrounds the stem for the purpose of holding the valve to its seat when the parts are not in motion. Each of these 100 valves is opened by means of a rod 50, one end of which is connected with one end of an arm 51, pivoted intermediate its ends as at 52 to a suitable fulcrum 53. An anti-friction roller 54 is journaled on the other 105 end of the arm which latter projects over the end of the stem 48 and in such a position that the roller will contact with the end of the stem. In order to overcome centrifugal force which would be generated by the rod 115 50 and that portion of the arm 51 which tends to open the valve, the rod and that portion of the arm between the pivot or fulcrum 53 and the rod, is constructed slightly heavier than the combined weight of the 120 other portion of the arm, the valve and the spring 49. The other end of each of the rods 50 projects into the crank case through a suitable bushing or collar 55, as shown more clearly in Fig. 1 and is operated so as to open 125 the valve in a manner which will now be described.

The cover plate 15 is provided on its inner face with recesses 56 which are arranged concentric with the opening 57 through 130

which the shaft 29 passes, and the shaft is provided adjacent the inner face of the cover plate with an eccentric cam portion 58. An external toothed gear 59 provided with a concentric central opening is connected with the shaft 29 through the medium of a bearing 60, preferably of the ball type which latter is arranged within the concentric opening of the gear and in which bearing the eccentric cam 58 is journaled.

An internal toothed gear 61 surrounds the gear 59 and the internal opening in the gear 61 is of a size greater than the external diameter of the gear 59, so that a portion only of the teeth of the gear 59 will be in mesh with the teeth of the gear 61 at any time, and the gears are so arranged with respect to each other that the teeth may be brought into mesh.

20 In the present form of the invention, and in which six cylinders are illustrated, the ratio of the gears 59—61, is substantially seventy two to eighty, but it is of course to be understood that in the event that the 25 number of cylinders is changed the ratio of these gears must necessarily be correspondingly altered.

The gear 61 is preferably in the form of a cam gear and is preferably provided with 30 cam projections 62 on its periphery and the cam projections are of such a size and are so located with respect to the extremities of the valve operating rods 50 that the projections will engage anti-friction rollers 63 carried by the ends of the rods, to shift the rods when the cam projections are moved into engagement therewith. In the present exemplification of this invention, five of these cam projections are shown, there being one 35 projection less than the number of cylinders for the reason that the parts are so constructed, that is, the cam gear 61, and the movement of this gear is so timed that the cam ring which travels upon the cover plate 40 45 to rotate in the same direction therewith but at a slower rate of speed, thereby necessitating the provision of only five cam projections for six cylinders, inasmuch as one of the cam projections will, by the 50 movement above set forth, assume a position to contact and shift the valve operating rod of the sixth cylinder by the time an explosion has been effected therein and after the exhaust valves of the remaining five 55 cylinders have been actuated. During this movement of the cam gear, the valve rods 50 will be operated in the order in which they are numbered in Fig. 4, that is to say, the rod A will be operated first, B second, C 60 third, D fourth, E fifth and F sixth.

The mechanism by which this movement of the cam gear 61 is produced will now be described.

The cam gear 61 is provided with a laterally projecting flange 64 which extends

over and is spaced from the periphery of an inwardly projecting lateral portion 65 on the cover plate 15 and the flange 64 is spaced from the periphery of the projecting portion 65 to form a raceway for the 70 balls 66 and the gears 59, 61 are arranged in close proximity to the inner face of the projecting portion 65 of the plate 15.

Projecting laterally from the gear 59 and in a direction to enter the recesses 56 in the 75 inner face of the plate 15 are stub axles 67, one for each of the recesses 56 and journaled upon these axles 67 by means of ball bearings 68 are anti-friction rollers 69 and the diameter of these anti-friction rollers is considerably smaller than the diameter of the recesses within which the rollers run. The rollers have engagement with the respective walls of the recesses 56 so that when the gear 59 is given a bodily eccentric motion 80 by the rotation of the shaft 29 and the eccentric 58, they will rotate within the recesses by their engagement with the walls of the recesses and they will also be given a bodily motion within the recesses by means 90 of the bodily motion of the gear 59.

It will therefore be seen, that inasmuch as the crank case and cylinders rotate in one direction and the shafts 25, 29, together with the propeller 32 and the eccentric 58 95 rotate in the opposite direction, a bodily movement will be given to the gear 59 in the same direction of movement as the direction of movement of the eccentric 58, and at the same time the gear 59 will be rotated 100 about the eccentric bearing and in the same direction as the direction of movement of the crank case. This rotation of the gear 59 about the eccentric 58 and in the same direction that the crank case is rotated, is 105 accomplished by means of the fact that the gear 59 is, so to speak, locked to the plate 15 through the medium of the anti-friction rollers 69 and the recesses 56, so that it will be manifest that even though there is a bodily oscillating movement imparted to the gear 59 by the rotation of the eccentric 58, a rotary motion of the gear 59 about the eccentric is effected through the medium of the plate 15.

110 This operation will cause the cam gear 61 to rotate in the same direction as the crank case, but at a different rate of speed to cause the respective cams 62 to successively engage the rollers 63 on the respective rods 50 120 to open the exhaust valves of the cylinders successively and in the order designated by the reference characters A, B, C, D, E, and F.

By the time the respective cam projections 125 have moved in the direction indicated by the arrow in Fig. 4 and the crank case moved in the direction of the arrow indicated in Fig. 4 to cause the projection to engage the respective rod, designated by the 130

reference character E, five of the cylinders will have been exhausted and the cam projection 62 which is shown in Fig. 4 as operating on the rod 50, and also designated by the reference character A will have traveled backwardly with respect to the direction of rotation of the crank case and the plate 15 so that it will engage the rod 50 also designated by the reference character 10 F, to operate the exhaust valve of the last or sixth cylinder.

This relative movement of the cam gear 61 with respect to the plate 15 of the crank case, is accomplished by means of the ratio 15 between the gears 59, 61 and this ratio should be such that upon each complete revolution of the plate 15 upon and with relation to which the gear 61 travels, the latter will have moved with respect to the direction 20 of rotation of the plate, a distance substantially equal to one fifth of the rotation of the plate. Obviously this ratio may be altered to suit the conditions existing and according to the number of cylinders employed.

The gears 59, 61 are held against lateral displacement longitudinally of the shaft 59 by means of the balls and ball races as will be understood.

30 The motor being of the four cycle type and assuming that there has been an explosion in the cylinder, the piston 18 will be at the limit of its inward movement after such explosion. The first movement of the piston 35 toward the explosion end after the explosion will force the burnt gases out of the exhaust. Upon the return of the piston, the valve 30^a will be released so that the suction in the cylinder will unseat the valve and a charge 40 of fuel will be drawn into the explosion end of the cylinder. Upon the next outward movement of the piston, the valve will be seated while the charge is being compressed and upon the next inward movement of the 45 piston although the valve will be released, it will not be unseated because it will be held to its seat by the pressure of the gases behind the valve.

While in the present form of the invention, the preferred forms and constructions have been shown and specifically described, which permit the parts to be compactly arranged and constructed of substantially light material, it is to be understood that 55 various changes may be made in the details of construction and arrangement of the parts within the scope of the claims, without departing from the spirit of this invention.

60 The explosion is effected in the cylinders by any well known form or type of electric sparking device.

While in the claims the terms plate and face plate have been employed, it is under-

stood that these terms are to be construed 65 in their broadest interpretation and to mean any form of support or rotating element, adapted to perform functions ascribed to the plate.

What is claimed as new is:

1. In a motor of the class described, the combination of a plurality of rotatable cylinders, a crank case connected therewith, a crank shaft rotatable in a direction opposite to the direction of rotation of the crank case 70 and cylinders, pistons in the cylinders and connected with the crank, a valve for each of the cylinders, a cam element rotatable in the same direction as the cylinders but at a slower rate of speed for opening the valves, 75 an operating element for rotating the cam element, and means for rotating the operating element in the same direction as the cylinders, the said means embodying mechanism whereby another and different bodily 80 movement with respect to the crank case will be imparted to the said operating element during its rotation.

2. In a motor of the class described, the combination of a plurality of rotatable cylinders, a crank case connected therewith, a crank shaft rotatable in a direction opposite to the direction of rotation of the cylinders and crank case, pistons in the cylinders and connected with the crank, a valve for each 90 of the cylinders, a cam element rotatable in the same direction as the cylinders but at a slower speed for opening the valves, an operating element for rotating the cam element, and means for rotating the operating element 95 in the same direction as the cylinders, the said means embodying mechanism whereby another and bodily rotary movement, with respect to the crank case, will be imparted to the said operating element during its 100 rotation.

3. In a motor of the class described, the combination of a plurality of rotatable cylinders, a crank case connected therewith, a valve for each of the cylinders, a cam element rotatable in the same direction as the cylinders but at a slower speed, for opening the valves, an operating element for rotating the cam element, and means for rotating the operating element in the same direction as the cylinders, the said means embodying mechanism whereby another and bodily rotary movement, with respect to the crank case, will be imparted to the said operating element during its rotation.

4. In a motor of the class described, the combination of a plurality of rotatable cylinders, a crank case connected therewith, a crank shaft rotatable in a direction opposite to the direction of rotation of the cylinders, pistons in the cylinders and connected with the crank, a valve for each of the cylinders, a cam element rotatable in

the same direction as the cylinders but at a slower speed for opening the valves, an operating element for rotating the cam element, and means for rotating the operating element in the same direction as the cylinders, the said means embodying mechanism whereby a bodily movement, with respect to the crank case, will be imparted to the said operating element simultaneously with its rotary movement.

5. In a motor of the class described, the combination of a plurality of rotatable cylinders, a valve for each of the cylinders, a cam element rotatable in the same direction as the cylinders but at a slower speed for opening the valves, an operating element for rotating the cam element, and means for rotating the operating element in the same direction as the cylinders, the said 15 means embodying mechanism whereby the said operating element will be rotated in the opposite direction during its first recited rotary motion.

6. In a motor of the class described, the combination of a plurality of rotatable cylinders, a crank shaft rotatable in a direction opposite to the direction of rotation of the cylinders, pistons in the cylinders and connected with the crank, a valve for each 30 of the cylinders, a cam element rotatable in the same direction as the cylinders but at a slower speed for opening the valves, an operating element for rotating the cam element, and means for rotating the operating element in the same direction as the cylinders, the said means embodying mechanism whereby the said operating element will be given a bodily rotation in the opposite direction during its first recited rotary motion.

40 7. In a motor of the class described, the combination of a plurality of rotatable cylinders, a crank case connected therewith, a crank shaft rotatable in a direction opposite to the direction of rotation of the cylinders, 45 pistons in the cylinders and connected with the crank, a valve for each cylinder, an internal toothed annular cam element for actuating the valves, an actuating gear within the cam element and of a diameter considerably less than the diameter of the opening in the element, means connecting the gear with the cylinders for rotation in the same direction therewith, and means for imparting a bodily rotary movement to the 55 said gear within the opening of the cam element and with respect to the crank case during the rotation of the gear.

8. In a motor of the class described, the combination of a plurality of rotatable cylinders, a valve for each cylinder, an internal toothed annular cam element for actuating the valves, an actuating gear within the cam element and of a diameter less than the diameter of the opening in the element,

means connecting the gear with the cylinders for rotation in the same direction therewith, and means for imparting a bodily rotary movement to the said gear within the opening of the cam element during the rotation of the gear and in a direction opposite to the direction of the first recited rotation of the gear.

9. In a motor of the class described, the combination of a plurality of rotatable cylinders, a valve for each cylinder, an internal toothed annular cam element for actuating the valves, an actuating gear within the cam element and of a diameter less than the diameter of the opening in the element, means connecting the gear with the cylinders for rotation in the same direction therewith, and eccentric means for imparting a bodily rotary movement to the said gear within the opening of the cam element during the first recited rotation of the said gear.

10. In a motor of the class described, the combination of a plurality of rotatable cylinders, a valve for each cylinder, an internal toothed annular cam element for actuating the valves, an actuating gear within the cam element and of a diameter less than the diameter of the opening in the element, means connecting the gear with the cylinders for rotation in the same direction therewith, and eccentric means for imparting a bodily rotation to the gear with respect to the cam element during the rotation of the gear.

11. The combination of a plurality of rotatable cylinders, a crank shaft rotatable in a direction opposite to the direction of rotation of the cylinders, pistons in the cylinders and connected with the crank, a valve for each of the cylinders, a rotatably supported annular internal toothed cam element for actuating the valves, a gear within the element and of a size less than the size of the opening in the element, and meshing with the teeth of the element, and means whereby the gear will be simultaneously rotated about its axis in one direction and also bodily rotated in a direction opposite to the first recited direction of rotation, to rotate the cam element.

12. The combination of a plurality of rotatable cylinders, a crank shaft rotatable in a direction opposite to the direction of rotation of the cylinders, pistons in the cylinders and connected with the crank, a valve for each of the cylinders, a rotatably supported annular internal toothed cam element for actuating the valves, a gear within the element and of a size less than the size of the opening in the element, and meshing with the teeth of the element, and means whereby the gear will be simultaneously rotated about its axis in one direction and also

- 6 bodily rotated in a direction opposite to the first recited direction of rotation, to rotate the same element, said cam element being provided with cam faces numbering one less than the number of cylinders.
13. The combination of a rotatable support, a plurality of cylinders connected therewith, a valve for each of the cylinders, an annular internal toothed cam element rotatably mounted upon the support for movement in the same direction as the direction of rotation of the support, a gear within the element and meshing with the teeth thereof, said gear being of a size considerably less than the size of the opening, means loosely connecting the gear with the support for rotating the gear in the same direction as the support, and cam means for imparting a bodily rotation to the gear in the same direction as the support but at a slower speed.
14. The combination of a rotatable support, a plurality of cylinders connected therewith, a crank rotatable in a direction opposite to the direction of rotation of the support, pistons in the cylinders and connected with the crank, a valve for each of the cylinders, an annular internal toothed cam element rotatably mounted upon the support for movement in the same direction as the direction of rotation of the support, a gear within the element and meshing with the teeth thereof, said gear being of a size considerably less than the size of the opening, means loosely connecting the gear with the support for rotating the gear in the same direction as the support, and cam means for imparting a bodily rotation to the gear in the same direction as the support but at a slower speed and during the rotation of the gear with and in the same direction as the support.
15. Valve actuating mechanism for motors of the class described, embodying a rotatable support, an annular member rotatably mounted upon the support, cam faces on the periphery of the member and teeth on the inner face of the member, a gear within the opening in the member and of a size considerably less than the opening, and means for supporting the gear for rotation about its axis in one direction and for bodily rotation in the opposite direction within the annular element.
16. Valve actuating mechanism for motors of the class described, embodying a rotatable support, an annular member rotatably mounted upon the support, cam faces on the periphery of the member and teeth on the inner face of the member, a gear within the opening in the member and of a size considerably less than the opening, means loosely connecting the gear with the support for rotation in the same direction therewith, and means eccentrically support-
- ing the gear with relation to the support whereby a bodily rotary movement will be imparted to the gear with relation to the support and within the annular member.
17. Valve actuating mechanism for motors of the class described, embodying a rotatable support, an annular member rotatably mounted upon the support, cam faces on the periphery of the member and teeth on the inner face of the member, a gear within the opening in the member and of a size considerably less than the opening, means loosely connecting the gear with the support for rotation in the same direction therewith, and means eccentrically supporting the gear with relation to the support whereby a bodily rotary movement will be imparted to the gear with relation to the support within the annular member and in a direction opposite to the first recited rotary movement of the gear.
18. Valve actuating mechanism for motors of the class described, embodying a rotatable plate, an annular cam element rotatably supported with respect thereto, said element having internal teeth, a gear within the opening of the element meshing with the teeth and of a size considerably less than the opening, said plate being provided with openings in its face adjacent the gear, means carried by the gear, projecting laterally therefrom and into the respective openings to form loose connections between the gear and plate whereby the gear will be rotated in the same direction as and simultaneously with the plate, and means for imparting a bodily rotation to the gear within the said element and with relation to the plate in a direction opposite to the direction of rotation of the plate.
19. Valve actuating mechanism for motors of the class described, embodying a rotatable plate, an annular cam element rotatably supported with respect thereto, said element having internal teeth, a gear within the opening of the element meshing with the teeth and of a size considerably less than the opening, said plate being provided with openings in its face adjacent the gear, means carried by the gear, projecting laterally therefrom and into the respective openings to form loose connections between the gear and plate whereby the gear will be rotated in the same direction as and simultaneously with the plate, and means rotatably supporting the gear eccentrically with relation to the plate whereby a bodily rotary motion will be imparted to the gear within the said element with relation to the plate and in a direction opposite to the direction of rotation of the plate.
20. Valve actuating mechanism for motors of the class described embodying a rotatable plate, an annular cam element rota-

tably supported with respect thereto, said element having internal teeth, a gear within the opening of the element meshing with the teeth and of a size considerably less than the size of the opening, said plate being provided with openings in its face adjacent the gear, anti-friction devices connected with the gear and projecting into the respective openings in the plate, said devices being of a size considerably smaller than the respective openings and engaging the walls of the openings for rotating the gear in the same direction as the plate, and

means for imparting to the gear a movement in a direction opposite to the direction of rotation of the plate to cause the said anti-friction devices to be bodily rotated within their respective openings in the plate. 15

In testimony whereof I have signed my name to this specification, in the presence 20 of two subscribing witnesses, on this 8th day of August, A. D. 1916.

THOMAS P. BROOKE.
